UNITED STATES PATENT OFFICE.

SIMON D. S. NARBER, OF MARSHALLTOWN, IOWA.

RAIL FASTENING AND TRACK STRUCTURE.

Application filed June 29, 1927. Serial No. 202,227.

This invention relates to rail fastenings and track structures, and has for one object to provide a track structure which shall furnish a means for securely positioning the track elements in their proper relation.

Another object is to provide an improved form of rail fastening which shall be positive in its action and readily applied to the rail.

A further object is to provide a rail fastening which shall securely hold the rail yet permit a considerable amount of flexibility to the rail with respect to the fastening.

With the above and other objects in view, my invention consists in the combination and arrangement of parts hereinafter described and claimed, and more particularly illustrated in the accompanying drawings, wherein

Figure 1 is a fragmentary plan view of one half of my improved track structure, the other half being substantially similar, and also showing my improved form of rail fastening.

Figure 2 is a side elevation of Figure 1, the rail being shown in section.

Figure 3 is a sectional view of Figure 2, and

Figure 4 is a detail of one of the rail clamps.

Referring now more particularly to the drawings, I show a railroad tie 10 of usual construction, having a tie plate 11 mounted thereon as by fastenings 24 passed through the center of the plate at the medial portion of the tie, and by track spikes 25 driven into the tie at the edges of the plate each side of the rail, only the head on the track spikes engaging the tie plate. The said tie plate 11 extends substantially coextensive with the tie 10, and has a plurality of rail supporting elements 12 mounted thereon suitably to the number of rails 13 to be supported by the tie. Each rail supporting element 12 has a groove 14 in its underside extending transversely of the rail 13, and also has laterally extending wings 15 for the purpose of fastening the said element to the tie plate, as by rivets 16. A rail clamp 17 is provided on each side of each rail supporting element 12 and associated therewith, and each clamp 17 comprises a body portion having an extended foot 18 for engaging the said groove 14, and an over-

hanging flange 19 for engaging the base of

the rail 13, the said flange having the rail base engaging face thereof formed with an arcuate shape, as shown at 20. Each rail clamp 17 is slidable transversely of the rail 13, and its body portion extends substantially laterally of the rail with the end 21 oppositely of the rail slidably passed through a U-shaped clamp engaging bracket 22 mounted on the tie plate 11. Locking means are provided in the bracket 22 for releasably locking the clamp 17 in engagement with the rail 13, said means, in the embodiment shown, comprising a bolt 23 releasably passed through the bracket and the clamp.

In use, for a single track structure, the tie 10, with the tie plate 11 thereon, has a rail 13 positioned near each of its ends, the said rail being positioned upon the rail supporting element 12. Each of the rail clamps 17 is then inserted through the brackets 22 so as to have the foot 18 engaging the groove 14 of the rail supporting element 12, and the flange 19 engaging the base of the rail. The bolt 23 is then passed through the bracket and the clamp, thus securely yet releasably locking the clamp in engagement with the rail.

The purpose of the arcuate shape of the rail base engaging face 20 of the clamp 17 is to prevent pinching of the rail base as a load passes over the tie, the effect of the load, as is well known, being to deflect and distort the rail. By my construction, this distortion of the rail is readily accommodated, thus preventing fractures of the rail base.

It will be readily seen that by mounting the tie plate on the tie as described, the said tie plate is free to expand at its ends, being fixed to the tie at its center, but slidably secured thereto elsewhere. In this manner I prevent buckling and distortion of the tie plate. Also, the tie plate acts to prevent the spreading of the rails, by securely tying the rail fastening means together.

I claim:

1. In a track structure, a tie, a plate mounted on the tie and substantially coextensive therewith, a plurality of rail supporting elements mounted on the plate, and a pair of rail engaging clamps removably connected with each of said rail supporting elements and mounted on said plate.

2. In a track structure, a tie, a plate

mounted on the tie and substantially coextensive therewith, a plurality of rail supporting elements mounted on the plate, a pair of rail engaging clamps slidably mounted on said plate connected with each of said rail supporting elements and releasably engaging the rail, clamp engaging brackets mounted on said plate, and locking means connected with each of said brackets engaging 10 one of said clamps.

3. In a rail fastening device, a rail supporting plate having a groove in its underside extending transversely of the rail, and a pair of rail clamps connected with the 15 supporting plate, each of said clamps comprising a body having an extended foot for engaging said groove, and an overhanging flange for engaging the rail base, said flange having the rail engaging face thereof formed with an arcuate shape, 20 with an arcuate shape.

4. In a rail fastening device, a tie plate, a rail supporting plate mounted on the tie plate and having a groove in its underside extending transversely of the rail, a pair of 25 rail clamps slidably mounted on the tie plate and connected with said rail supporting plate, each of said clamps comprising a body having an extended foot for engaging said groove, and an overhanging flange for 30 engaging the rail base, said flange having the rail engaging face thereof formed with an arcuate shape, clamp engaging brackets 35 mounted on the tie plate, each of said brackets having locking means connected therewith for engaging one of said clamps.

5. In a rail fastening device, a rail supporting plate having a groove in its underside extending transversely of the rail, a rail clamp on each side of the rail connected 40 with the supporting plate, each of said

clamps comprising a body having an extended foot for engaging said groove and an overhanging flange for engaging the rail base, said flange having the rail base engaging face thereof formed with an arcuate 45 shape, and means for releasably positioning said clamps in engagement with said rail.

6. In a track structure, a tie, a tie plate mounted on the tie and substantially coextensive therewith, a plurality of rail supporting plates each having a groove in its underside extending transversely of the rail, a rail clamp on each side of each rail supporting plate and connected therewith, each clamp comprising a body having an extending foot for engaging said groove and an overhanging flange for engaging a rail base, 50 said flange having the rail base engaging face thereof formed with an arcuate shape, each rail clamp being slidable transversely 55 of the rail, and means connected with said tie plate for releasably locking said clamp in engagement with said rail.

7. In a rail fastening device, a tie plate, a rail supporting plate mounted on the tie plate and having a groove in its underside extending transversely of the rail, a rail clamp mounted on the tie plate, slidably 60 transversely of said rail, each clamp comprising a body having an extended foot for 65 engaging said groove, and an overhanging flange for engaging the rail base, said flange having the rail engaging face thereof formed with an arcuate shape, a clamp 70 engaging bracket connected with each clamp and mounted on the tie plate, and locking means on the bracket for releasably locking the clamp in engagement with the rail.

In testimony whereof I affix my signature.
SIMON D. S. NARBER.
